SEALING CLOSURE

Filed Oct. 23, 1944

UNITED STATES PATENT OFFICE

2,557,827

SEALING CLOSURE

Carroll P. Krupp, Barberton, Ohio, assignor to
The B. F. Goodrich Company, New York, N. Y.,
a corporation of New York

Application October 23, 1944, Serial No. 559,954

8 Claims. (Cl. 24—205.1)

1

The invention relates to closures for sealing adjacent margins and especially to sealing slide fastener structures.

This application is a continuation-in-part of my co-pending application for Sealing Closure, Serial No. 509,427, filed November 8, 1943, now matured into Patent No. 2,545,817, dated March 20, 1951.

Objects of the invention are to provide for closing and sealing effectively adjacent separable margins of a structure at a face thereof; to provide for maintaining the seal despite flexure of the margins; to provide closure means including sealing elements having outwardly extending sealing portions at said face for sealing by lip-action of said portions; to provide protecting means for guarding against accidental breakage of the seal; to provide for assuring the positioning of the sealing elements in sealing relation with one another; to provide for resisting objectionable flexure of the margins tending to separate such elements; and to provide simplicity of construction, convenience of manufacture and effectiveness of operation.

These and other objects and advantages of the invention will be apparent from the following description.

In the accompanying drawings, which form a part of this specification, and in which like numerals are employed to designate like parts throughout the same,

Fig. 1 is a perspective view of a sealing closure constructed in accordance with and embodying the invention, parts being broken away and in section,

Fig. 2 is a sectional view of the respective components of the closure as such components are molded, the sealing margins being shown in separated condition,

Fig. 3 is a perspective view of the closure including an end thereof mounted on the wall of a hollow article, parts being broken away and in section,

Fig. 4 is a perspective view of a modification of the sealing closure, parts being broken away and in section,

Fig. 5 is a view like Fig. 4, but showing a runner in engaging relation with parts of the closure, and

Fig. 6 is a perspective view of a further modification of the sealing closure, parts being broken away and in section.

In the embodiment of the invention illustrated in Figs. 1, 2 and 3, the sealing closure includes preferably a slide fastener structure 10 for de-

2

tachably uniting adjacent margins 11 and 12 of an article 13 to be fastened, and includes sealing elements 14 and 15 of suitable elastic material such, for example, as resilient rubber or other rubber-like material, which overlie fastener elements 16 and 17 of such structure.

The slide fastener structure 10 includes flexible margins or stringers 18 and 19 of suitable material such, for example, as woven fabric of cotton, linen, silk, rayon or other suitable material, which stringers may be coated or impregnated with resilient rubber or other rubber-like material 20 and 21 for fluid-sealing purposes and for facilitating adhesively attaching the stringers to the separable margins 11 and 12 of an article 13, which may be a garment, container, tent or other structure as to which a sealing closure is desired.

Adjacent marginal edges of the stringers are provided with beads 22 and 23 of cords of suitable filamentary material attached, as by sewing 24 at each face of the stringers and extending continuously along such edges. The spaced-apart cooperating fastener elements 16 and 17 are mounted in series upon each of the stringers at 25 said marginal edges, engaging the material of the beads 22 and 23 and the stringers 18 and 19. The fastener elements include engaging portions 25 and 26 and mounting portions 27 and 28 and may be of metal, plastic or other suitable stiff material having the desired strength characteristics. A slider or runner 29 of suitable known construction, including a top plate element 30, a channeled bottom plate element 31 and a pull tab 32, may be used for engaging and disengaging the 30 opposing series of fastener elements 16 and 17, the runner being slidable along the respective series of elements.

For closing and sealing the separable margins 18 and 19 of the structure 10, the sealing elements 14 and 15 may be mounted directly on the mounting portions 27 and 28 of the fastener elements 16 and 17 and are positioned in lip-sealing contact with one another at adjacent outwardly extending sealing portions 37 and 38 in the manner shown especially in Fig. 1. Since the sealing elements may be made of suitable rubber material, they may be molded directly upon and adhered by a vulcanized bond to the mounting portions 27 and 28 of the fastener elements and extend continuously along the beaded marginal edges of the stringers, bridging the spaced-apart fastener elements of the respective series at such edges and extending over the ends of the fastener elements into continuity with the rubber layers 20, 21 of the stringers. The rubber ma-

terial of such sealing elements is positioned in the interstices between adjacent fastener elements at the mounting portions 27 and 28 thereof; but the interstices between such fastener elements at the engaging portions 25 and 26 thereof are free of the rubber material of the sealing elements so that relative movement of the fastener elements for opening and closing the slide fastener structure will not be objectionably restricted. This arrangement has the additional advantage of resiliently holding the fastener elements in alignment for facilitating and assuring coaction between the latter during the engaging and disengaging operations of the sealing closure.

The sealing elements 14 and 15 are generally L-shape in section providing base portions 33 and 34 positioned at the mounting portions 27 and 28 of the fastener elements and marginal portions 35 and 36 extending laterally from the base portions and overlying the engaging portions 25 and 26 of the fastener elements in separated relation thereto, thereby providing space for the free sliding movement of the top plate element 30 of the runner 29 along the faces of the respective series of engaging portions 25 and 26 of said fastener elements.

In accordance with the invention, the marginal portions 35 and 36 include sealing portions 37 and 38 tapering to edges 39 and 40 and extending generally normal to the face of the structure 10 in position for sealing by lip-action of such edges against one another. The relative positions of the sealing elements in the "as molded" and non-flexed condition and before engagement of the fastener elements with one another are shown especially in Fig. 2, the margins or stringers 18 and 19 being in a separated condition.

The marginal portions 35 and 36 including the sealing portions 37 and 38 may terminate at or short of the ends of the fastener elements for facilitating flexing contact of such sealing portions with one another, especially at the region of the edges 39 and 40 thereof. The adjacent faces of the sealing portions 37 and 38 may be substantially smooth sealing surfaces 41 and 42 extending outwardly in the generally on substantially normal direction to the face of the structure 10, that is more nearly in the true normal direction than in the direction parallel to said face, which sealing surfaces may be angularly inclined relative to one another for promoting resilient lip-action sealing by the edges 39 and 40 by virtue of the flexure of the tapered portions 37 and 38. The marginal portions 35 and 36 of the sealing elements also include protecting portions 43 and 44, preferably of generally rounded contour adjacent and spaced from the sealing portions 37 and 38, which portions 43 and 44 protrude outwardly to at least the height of the edges 39 and 40 for guarding such edges against accidental separation thereof and breakage of the fluid-tight seal of the closure.

For closing in a detachable manner the separable margins 11 and 12 of an inflatable article 13, for example, having flexible wall portions of suitable impervious fabric material, the sealing closure may be attached to the flexible margins 11 and 12 such that the sealing elements 14 and 15 are positioned within the interior of such article for protection purposes and for functioning in cooperation with the internal pressure to further assure a fluid-tight seal. The fabric stringers 18 and 19 of the slide fastener structure 75

10 may be attached to the margins 11 and 12 by means of a suitable adhesive 45 such, for example, as rubber cement, or by sewing 46, or both, such that the rubber coatings 20 and 21 on such stringers may be positioned against the fabric wall of the article.

The respective ends of the sealing closure may be sealed and closed in the manner shown especially in Fig. 3, and for purposes of description, since both ends may be identical, the construction at one end at 51 only will be described in detail. End portions 47 and 48 of the sealing elements 14 and 15 are arranged with the sealing surfaces 41 and 42 in contact and the sealing portions 37 and 38 at portions 47 and 48 are secured together as by a suitable adhesive at such surfaces. A tape element 50 of suitable rubber material may be adhesively secured at the end at 51 to the wall of the article 13 and to the end portions 47 and 48, overlapping such wall and end portions and conforming smoothly to the extreme ends at 49 of such portions thereby completing the sealing of the closure at the end at 51.

In the operation of changing the sealing closure 25 from the closed condition shown especially in Fig. 1 to the open condition shown especially in Fig. 3, the slider or runner 29 is manipulated along the fastener elements 16 and 17 in the direction, for example, away from the end at 51. Such movement of the runner disengages the fastener elements coincidental with separating the sealing elements 14 and 15 and positioning the latter elements in spaced-apart relation to one another by virtue of their transverse movement with respect to the longitudinal center line of the slide fastener structure, since such sealing elements are mounted directly upon the fastener elements 16 and 17. In this manner the sealing portions 37 and 38 are separated and permitted to flex and resume the "as molded" position, as shown especially in Fig. 2, the edges 39 and 40 thereof being no longer in contact for sealing by lip-action. With sealing closure in the open condition, a body or material may be admitted into or removed from the hollow article 13 through the opening defined by the separated margins 11 and 12 and stringers 18 and 19.

The sealing closure is returned to the closed condition by moving the runner 29 in the direction toward the end at 51, which movement of the runner re-engages the fastener elements and draws together the sealing elements 14 and 15. This drawing action brings the sealing portions 37 and 38 into flexing contact with one another, whereby the edges 39 and 40 contact one another and the sealing surfaces 41 and 42 wholly or partially contact one another substantially throughout their entire extent in the outward direction, as shown especially in Fig. 1. In this manner the separable margins 11 and 12 of the article 13 and the stringers 18 and 19 of the slide fastener structure 10 are closed and sealed fluid-tight by the lip-action of the sealing elements. Pressure within the article further assists in maintaining such seal by the pressing action of such pressure upon the exposed surfaces of the sealing elements, especially at the region of the edges 39 and 40. By virtue of its construction and arrangement, the sealing closure maintains its sealed condition despite flexure and twisting to a reasonable extent of the margins thereof; since the sealing portions 37 and 38 may move relative to one another and the edges 39 and 40 thereof may move likewise against and along the respective surfaces 41 and 42, thereby maintain-

ing lip-sealing contact with such surfaces throughout the flexing and twisting of the closure.

The modified construction 55 shown in Figs. 4 and 5 is, in some of its aspects, like the sealing closure shown in Figs. 1 to 3, inclusive, especially with respect to sealing by lip-action. The modified construction 55 includes a slide fastener structure 56 including separable stringers 57 and 58 of suitable fabric material and fastener elements 59 and 60 attached along adjacent margins of such stringers, which margins have beads 61 and 62 suitably attached to such margins, the beads being of suitable cord material. A runner 63 substantially like the runner 29 provides for engaging and disengaging the cooperating fastener elements 59 and 60.

Sealing elements 64 and 65 of suitable resilient rubber material are positioned at a face of the slide fastener structure 56, which elements may be mounted directly upon the stringers 57 and 58 instead of upon the fastener elements, as in the construction shown in Fig. 1. The sealing elements 64 and 65 are separated from the fastener elements 59 and 60 to provide space for receiving the runner 59 without binding against such runner, the sealing elements being desirably generally L-shaped in section. Such sealing elements include sealing portions 66 and 67 tapering in section to edges 68 and 69 and extending generally on substantially normal to the face of the structure 56 in position for sealing by lip-action of said edges against one another. The sealing portions 66 and 67 may be provided with substantially smooth sealing surfaces 70 and 71 extending outwardly in the generally on substantially normal direction to the face of the structure 56, which sealing surfaces may be angularly inclined relative to one another for promoting lip-action sealing by the edges 68 and 69 of the sealing portions 66 and 67. The sealing elements also include protecting portions 72 and 73, preferably of generally rounded contour adjacent and spaced from the sealing portions 66 and 67, which portions 72 and 73 protrude outwardly to at least the height of the edges 68 and 69 for guarding such edges against accidental separation thereof and breakage of the fluid-tight seal of the closure.

For the "as molded" condition, the sealing elements 64 and 65 including sealing portions 66 and 67 extend to or short of the ends of the respective slide fastener elements 59 and 60. Sealing coatings 74 and 75 of suitable resilient rubber-like material in continuation of the sealing elements 64 and 65 may be provided on the stringers 57 and 58 at said face of the slide fastener structure 76. The sealing elements and the coatings may be secured to the fabric stringers 57 and 58 as by a vulcanized bond and molded and vulcanized under heat and pressure.

For bracing and supporting the sealing elements 64 and 65 to prevent and further guard against accidental breakage of the lip seal under objectionable relatively severe twisting and flexing of the slide fastener structure 56, there is provided at the opposite face of the structure 56 a pair of bracing elements 76 and 77 of suitable resilient rubber-like material. The bracing elements 76 and 77 may be generally L-shape in section providing base portions 78 and 79 and marginal portions 80 and 81 extending laterally from the base portions, the marginal portions 80 and 81 having desirably flat sealing surfaces extending generally normal to said opposite face of the slide fastener structure 56 and adapted for

abutting relation with one another. The base portions 78 and 79 are positioned closely adjacent the ends of the fastener elements 59 and 60, as shown especially in Fig. 4, and such base portions are positioned opposite the corresponding base portions of the sealing elements 64 and 65. Sealing coatings 82 and 83 of suitable rubber-like material in continuation of the bracing elements 76 and 77 may be provided on the stringers 57 and 58 at said opposite face of the slide fastener structure, and such coatings 82 and 83 and the bracing elements 76 and 77 may be secured thereto as by a vulcanized bond and molded and vulcanized under heat and pressure.

The bracing elements 76 and 77 are so constructed and arranged that, for the closed condition of the closure 55, the marginal portions 80 and 81 are in abutting contact with one another at the sealing surfaces; and the bracing elements 20 present a continuous truss-like wall extending between the base portion of the sealing element 64 and the base portion of the sealing element 65, whereby such bracing elements support the stringers 57 and 58 and the sealing elements 64 and 65 to prevent separation of the latter under objectionable bending and twisting of the sealing closure.

In the sealing closure 55 of Figs. 4 and 5 the runner 63 has a channeled top plate element 84 positioned for engaging the fastener elements 59 and 60 and positioned within the space defined by the sealing elements 64 and 65 overlying such fastener elements. The runner 63 has a flat bottom plate element 85 positioned adjacent 30 the fastener elements and within the space defined by the bracing elements 76 and 77, which bottom element includes an outwardly projecting portion 86 extending between the abutting surfaces of the marginal portions 80 and 81, as shown especially in Fig. 5. A pull tab 87 is in engaging and pivoting relation with the projecting portion 86 of the runner, whereby the runner may be manipulated from said opposite face of the slide fastener structure 56.

The sealing closure 55 may be positioned on the separable margins of the article 13 substantially in the same manner as described hereinabove for the construction shown in Figs. 1 to 3, inclusive, the sealing elements 64 and 65 being 40 at the interior and the bracing elements being at the exterior of the article. This arrangement permits sealing effectively the opening in the wall of the article while protecting the sealing elements, including the sealing portions thereof, against breakage of the lip-seal and while 50 permitting conveniently operating the closure from the exterior of the bag. The bracing elements 76 and 77, in addition to functioning as bracing means for the sealing elements, also 55 function advantageously to protect the fastener elements against the entrance, for example, of objectionable dirt and fluid.

In the operation of opening the sealing closure 55, the runner 63 is manipulated along the fastener elements 59 and 60 in a direction such 65 that the fastener elements are disengaged, for example, and the stringers 57 and 58 are spread apart. Coincidental with the spreading action of the stringers, the sealing elements 64 and 65 and the bracing elements 76 and 77 are separated or moved transversely relative to one another, breaking the seal of the closure, the edges 68 and 69 of the sealing elements 64 and 65 no longer being in contact with one another and 70 the sealing portions 66 and 67 assuming the po-

sition of "as molded." In manipulating the runner 63, the portion 86 thereof extending between the bracing elements 76 and 77 slides along such elements between their abutting surfaces.

For returning the sealing closure to the closed condition, the runner 63 is manipulated in the opposite direction, thereby engaging the fastener elements and drawing together the sealing elements 64 and 65 and the bracing elements 76 and 77 such that the bracing elements resume their abutting relation at the adjacent ends of the marginal portions 80 and 81 and the sealing portions 66 and 67 flex into lip-sealing contact at the edges 68 and 69 thereof. The bracing elements 76 and 77 assure the proper positioning of the sealing elements for resumption of their sealing relation by lip-sealing action. Since the marginal portions of the bracing elements 76 and 77 press against one another at their adjacent ends, they likewise may press against and substantially conform to the projecting portion 86 of the runner, substantially sealing thereagainst by virtue of the resiliency of the rubber material of such elements. In this manner the sealing closure 55 closes effectively the adjacent margins despite a pressure differential at such margins, and effectively protects against accidental breakage of the seal, and also protects the fastener elements of the slide fastener structure 56 against objectionable exposure to the weather and entrance of materials such, for example, as water and dirt.

The modified construction 90 of the sealing closure shown in Fig. 6 is, in some of its aspects, substantially like the sealing closure 55, and includes a slide fastener structure 91 comprising stringers 92 and 93 of suitable fabric material, beads 94 and 95 on adjacent margins thereof, and cooperating fastener elements 96 and 97 suitably secured in series at such margins. The fastener elements are engaged and disengaged by a suitable runner 98, which is substantially the same as the runner 63 except as to channelled top and bottom plate elements. The stringers 92 and 93 may be provided with impervious coatings 98, 99, 100, 101 and 102 of suitable rubber-like material.

Sealing elements 104 and 105 of suitable resilient rubber-like material are positioned at a face of the structure 91 for closing the adjacent stringers by lip-action sealing. The sealing elements 104 and 105 may be generally L-shape in section providing base portions 106 and 107 on the stringers and marginal portions 108 and 109 extending laterally from the base portions and overlying the fastener elements 96 and 97. The sealing elements are separated from the fastener elements, whereby space is provided for the top plate element 110 of the runner 98.

The marginal portion 109 of the sealing element 105 includes a sealing surface 111 extending generally on substantially normal to said face of the structure 91, and such marginal portion 109 also includes a generally rounded protecting portion 112 adjacent the sealing surface 111. The marginal portion 108 of the sealing element 104 includes a sealing portion 113 tapering to an edge 114 and extending generally or substantially normal to said face of the structure 91 in position for sealing by lip-action of the edge 114 against the sealing surface 111. The marginal portion 108 also includes a protecting portion 115 of generally rounded contour adjacent and spaced from the sealing portion 113 for guarding such edge and preventing accidental

breakage of the seal. Upon engagement of the fastener elements 96 and 97, the sealing elements 104 and 105 are positioned such that the sealing portion 113 is flexed such that the edge 114 is resiliently held in lip-sealing contact with the sealing surface 111, while opposing areas 116 and 117 trailing such edge may be in contact with one another or may be maintained in separated relation, as shown especially in Fig. 6.

At the opposite face of the slide fastener structure 91, bracing elements 118 and 119 are positioned substantially in the manner as described for the sealing closure 55, except that such bracing elements are in spaced relation throughout their extent with the fastener elements 96 and 97 and base portions 120 and 121 thereof may be positioned directly opposite the corresponding base portions 106 and 107 of the sealing elements 104 and 105. The marginal portions 122 and 123 of the bracing elements 118 and 119 are adapted for abutting relation throughout their extent and press against one another in substantially sealing contact. The runner 98 has a projecting portion substantially like the projecting portion 86 of the runner 63, which projecting portion of the runner 98 extends between the bracing elements 118 and 119 as described hereinabove for the closure 55.

The sealing closure 90 is placed in the open and closed conditions, respectively, substantially in the same manner described for the sealing closure 55, by manipulation of the runner 98, first in one direction and then in the opposite direction, to engage and disengage the fastener elements 96 and 97, thereby separating and engaging the bracing elements and the sealing elements, respectively.

Variations may be made without departing from the scope of the invention as it is defined in the following claims.

I claim:

1. A sealing closure comprising a slide fastener structure having a pair of stringers and cooperating fastener elements at the margins of said stringers, and a pair of sealing elements generally L-shape in section providing base portions mounted at said fastener elements and free portions extending laterally from said base portions toward each other and overlying said fastener elements at a face of said structure, one of said free portions having a sealing surface extending substantially normal to said face and the other of said free portions having a marginal portion tapering to an edge and said other free portion presenting a second sealing surface extending substantially normal to said face and continuing to said edge, said sealing element being disposable with said sealing surfaces substantially in opposition and in position for sealing by lip-action of said edge against the first said surface, and means for bracing said sealing elements against separation from one another, said means comprising elements generally L-shape in section providing base portions on said stringers at the other face of said structure and portions extending laterally from said base portions toward each other and adapted to cooperate in abutting relation with one another for resisting flexure of said stringers tending to separate said sealing elements at said sealing surfaces.

2. A sealing closure comprising a slide fastener structure having a pair of stringers and cooperating fastener elements at the margins of said stringers, a pair of sealing elements gen-

erally L-shape in section providing base portions mounted on said stringers at said fastener elements and free portions extending laterally from said base portions toward each other and overlying said fastener elements at a face of said structure, said free portions tapering to edges and presenting sealing surfaces extending substantially normal to said face and continuing to said edges, said sealing elements being disposable with said sealing surfaces substantially in opposition and in position for sealing by lip-action of said edges and having protecting portions adjacent said sealing surfaces for guarding said edges, and means for bracing said sealing elements against separation from one another, said means comprising elements on said stringers at the opposite face of said structure adapted to cooperate in abutting relation with one another for resisting flexure of said stringers tending to separate said sealing elements at said sealing surfaces.

3. A sealing closure comprising a structure having a pair of separable margins, both of which are subject to flexure, separable fastener elements at said margins interengaging one another and detachably uniting the margins in the closed condition of the closure, a flexible element on one of said margins at a face of the margins presenting a sealing surface extending substantially normal to said face, a flexible sealing element on the other of said margins at said face having a marginal portion overlying said fastener elements and tapering to an edge in the direction away from and substantially normal to said face and said sealing element presenting a second sealing surface extending substantially normal to said face and continuing to said edge, said sealing element being disposable with said sealing surfaces substantially in opposition and inclined toward one another in the open condition in position for sealing by lip-action of said edge against the first said sealing surface in the closed condition, and means at the other face of said margins and additional to said fastener elements for bracing said sealing element against separation from the first said sealing surface under flexure of said margins.

4. A sealing closure comprising a structure having a pair of separable margins, slide fastener means including fastener elements for detachably uniting said margins, sealing elements mounted directly on said fastener elements at a face of the margins for closing the latter, said sealing elements having marginal portions tapering to edges and said sealing elements presenting sealing surfaces extending substantially normal to said face and continuing to said edges, said sealing elements being disposable with said sealing surfaces substantially in opposition and in position for sealing by lip-action of said edges, and means at the other face of said margins additional to said fastener elements for bracing said margins against flexure tending to separate said edges from one another.

5. In a slide fastener structure comprising a pair of stringers and cooperating fastener elements at the margins of said stringers, in combination, a pair of sealing elements each mounted at said fastener elements of a stringer and overlying said fastener elements at a face of said structure, said sealing elements having free portions overlying said fastener elements and projecting laterally of said structure toward one another, said free portions tapering to edges remote from said fastener elements in the direc-

tion normal to said face and presenting substantially flat sealing surfaces extending substantially normal to said face and continuing to said edges with said sealing surfaces substantially in opposition and in contact with one another at portions thereof immediately adjacent said edges and the remaining portions of said sealing surfaces in spaced-apart relation to one another in the closed condition of the fastener, and bracing elements at the other face of said structure adapted to cooperate in abutting relation with one another for bracing said sealing elements against separation.

6. A sealing closure comprising a structure having a pair of separable adjacent margins both of which are subject to flexure and detachably united in the closed condition of the closure, sealing elements of flexible material on said margins at a face of the structure, said sealing elements having elastic marginal portions extending laterally toward each other and tapering to edges remote from said margins in the direction away from and substantially normal to said face and said sealing elements presenting sealing surfaces extending substantially normal to said face and continuing to said edges, said sealing elements being disposable with said sealing surfaces substantially opposite and inclined toward one another in the open condition in position for sealing by lip-action flexure of said edges in the closed condition, and means for bracing said sealing elements against separation from one another, said means comprising elements of flexible material on said margins disposed wholly at the opposite face of said structure and having lateral portions adapted to cooperate in abutting relation with one another for resisting flexure of said margins tending to separate said sealing elements at said sealing surfaces.

7. A sealing closure comprising a structure having a pair of separable adjacent margins both of which are subject to flexure and detachably united in the closed condition of the closure, separable fastener elements at the adjacent edges of said margins interengaging one another and detachably uniting the margins in the closed condition of the closure, a flexible element on one of said margins at a face of the structure and presenting a sealing surface extending substantially normal to said face, a sealing element of resilient rubber-like material generally L-shaped in section providing a base portion on the other of said margins at said face of the structure and a free portion extending laterally from said base portion toward said flexible element and overlying said fastener elements, said free portion tapering to an edge remote from said fastener elements in the direction away from and substantially normal to said face and presenting a second sealing surface extending substantially normal to said face and continuing to said edge, said sealing element being disposable with said sealing surfaces substantially opposite and relatively inclined toward one another in the open condition in position for sealing by lip-action flexure of said edge of the sealing element against the first said sealing surface in the closed condition, and means comprising flexible material additional to said margins and said fastener elements at the other face of said structure for bracing said sealing element against separation from the first said sealing surface under flexure of said margins.

8. In a slide fastener structure comprising a pair of flexible stringers and cooperating teeth

11

at the adjacent margins of said stringers, in combination, a pair of sealing elements of resilient rubber-like material on said stringers adjacent said teeth at a face of said structure, said sealing elements having free portions overlying said teeth in spaced-apart relation thereto and projecting laterally of said structure toward one another, said free portions tapering to edges remote from said teeth in the direction away from and substantially normal to said face and presenting sealing surfaces extending substantially normal to said face and continuing to said edges, said sealing surfaces being substantially opposite and inclined toward one another in the open condition of the closure and being in contact with one another at least at portions thereof immediately adjacent said edges in the closed condition, and bracing elements of resilient rubber-like material generally L-shaped in section providing base portions on said stringers at the other face of said structure and portions extend-

5

12

ing laterally from said base portions toward each other and adapted to cooperate in the closed condition in abutting relation to one another for resisting flexure of said stringers tending to separate said sealing elements at said sealing surfaces.

Certificate of Correction

Patent No. 2,557,827

June 19, 1951

CARROLL P. KRUPP

It is hereby certified that error appears in the printed specification of the above numbered patent requiring correction as follows:

Column 1, line 38, after "in" insert *a*; column 3, line 48, column 5, lines 29 and 30, 35, and column 7, line 62, for "generally on" read *generally or*; column 9, line 57, after "edges" insert a comma;

and that the said Letters Patent should be read as corrected above, so that the same may conform to the record of the case in the Patent Office.

Signed and sealed this 4th day of March, A. D. 1952.
